FOLDING PLOW ANCHOR

William Scott Farren, Cambridge, England, assignor to The Security Patent Anchor Company Limited, London, England, a British company

Application August 13, 1947, Serial No. 768,316
In Great Britain August 19, 1946

6 Claims. (Cl. 114—206)

1

This invention relates to anchors of the kind comprising a fluke in the general form of a double-bladed ploughshare symmetrical about a central ridge formed by the junction of the two blades and sloping downwardly towards a point. Anchors of this kind are described in Patent No. 1,974,933, issued September 25, 1934. The anchors of this kind may be provided with a shank pivotally attached to the fluke for relative swinging movements about an axis which lies in the plane of symmetry and intersects the ridge in the region of the point. The shank may comprise two rigid portions, whereof one is rigidly fixed to the fluke or forms part thereof and extends outwardly from the central ridge in the plane of symmetry and the other is adapted to extend forwardly of the fluke and is pivotally attached to the rigid portion for relative swinging movements about an axis as aforesaid.

Anchors of the above kind are particularly suited for use on comparatively small boats in which they are stored on deck when not in use. When stored in this way, however, they are apt to form an obstruction on the deck and they have the additional disadvantage that by virtue of their shape there is considerable risk of ropes getting caught around the projections of the anchor. It is an object of the present invention so to improve anchors of the above kind that when stored they will form less of an obstruction and there will be a reduced risk of ropes or other gear being caught on the projections of the anchors.

The invention provides an anchor of the kind described in which one or each blade of the fluke is constructed in two parts arranged for relative hinging movement whereby the blade or blades may be folded to reduce the height of the fluke when stored on its side.

In the preferred form of the present invention, the blade or each blade is divided along a line parallel to the central ridge, i. e. when the blade is of cylindrical form along a line parallel to the axis of the cylinder of which the blade forms a part. Preferably the position of the dividing line and the arrangement are such that when folded the point of maximum thickness of the shank, the maximum height of the fixed portion of the fluke (i. e. the ridge portion) and the tip of the folded part of the blade lie in approximately the same plane. The divided edge of the folded part of the blade should not lie above the plane aforesaid and may also lie approximately in the plane.

In one construction according to the invention both blades are divided as aforesaid and are

2

hinged about separate axes within the fluke and spaced from the dividing lines.

With a view to minimising the risk of ropes getting caught in the gap between the two parts of the blades when folded, means may be included in the anchor for fairing any gap there may be between the folded part of the blade and the fixed part.

A specific embodiment of an anchor incorporating the above and other features of the invention will now be described by way of example and with reference to the drawings accompanying the provisional specification:

Figure 1 is a side elevation of the anchor,

Figure 2 is an under-plan of the anchor,

Figure 3 is a rear view of the anchor lying on its side,

Figure 4 is a view corresponding to Figure 3 but showing the blades in the folded position, and

Figure 5 is a plan view of the anchor as shown in Figure 4.

The anchor forming the subject of this example has the general shape of that forming the subject of patent specification 1,974,933 and operates in the manner described in that specification. Each blade 1 of the fluke is divided along a line 2 which is parallel to the ridge 3 of the fluke and is also parallel to the axis of the cylinder of which the blade forms a part. The hinged portion 4 of each blade is provided with spaced lugs pivotally supported on hinge pins 6 which are themselves supported by lugs 7 on a plate 8 extending between and secured to the fixed portions 9 of the blades.

The nose or point of the fluke is weighted by a cast fillet 10 secured within the fluke and filling the space between the blades. This fillet is divided into three portions of which one is permanently secured between the fixed portion of

the blades at the point of the fluke and of which the other two 11 and 12 are secured to the divided portions of the blades respectively. The arrangement is such that, as shown in Figure 5, when the blades are folded the parts 11 and 12 fair-off the gap between the fixed and movable portions of the blades.

Extending between the movable portions of the blades near their rear ends there is a cross-stay 13 attached to brackets 14 on the inside of the blades. The stay is in the form of a bar bent at right-angles at its two ends, the bent portions passing through holes in the brackets 14 from the front side towards the rear faces of the brackets. At one end of the stay there is permanently fixed a knob or enlargement 15 and

at the other end of the stay there is a hole 16 through which a cotter pin may be passed to lock the stay in position. Any other suitable method of locking the stay may be employed if desired.

When it is desired to fold the anchor the cotter pin or other locking means for the stay 13 are released and the corresponding end of the stay is disengaged from the associated bracket 14. The bent portion at the other end of the stay 10 is then threaded through the corresponding bracket 14 to bring the length of the stay parallel to the ridge of the fluke. The two folding portions of the blades are then brought together into the position shown in Figure 4.

The position of the dividing lines 2 in the width of the blades and the position of the hinges are of importance. These positions are preferably so chosen that, as shown in Figure 4, when the anchor is folded the tips of the abutments 17 on the shank, the edges 18 of the fixed portions of the blades, the edges 19 and the tips 20 of the folding portions of the blades all lie in substantially the same planes so that the height of the anchor nowhere exceeds that of the abutments 17 below which is cannot be reduced.

The invention is not restricted to the precise constructional details described in the above example and illustrated in the drawings. For instance, the cross-stay 13 is not necessarily in the form of a rigid bar as described but may be divided in its length and provided with a toggle joint to hold it in the extended position.

I claim:

1. A folding plough anchor comprising a pair of blades extending on either side of a plane, said blades coming together in a ridge in said plane and sloping away from each other in the form of a double-bladed ploughshare, each of said blades comprising two parts which have adjacent edges when the anchor is unfolded for use, and hinge means connecting said parts of each blade for relative swinging movement about an axis generally parallel to said plane, whereby the height of the anchor is reduced by folding the blades when the anchor is stored on its side.

2. A folding plough anchor comprising a pair of blades extending symmetrically on either side of a plane, said blades coming together in a ridge in said plane and sloping away from each other in the form of a double-bladed ploughshare, each of said blades comprising a fixed portion rigidly connected to the fixed portion of the other blade and an outer hinged portion forming an extension of the fixed portion when the anchor is unfolded, and hinge means connected between the two portions of each blade with the hinge axis spaced from the blade toward said plane and extending generally parallel to said plane, whereby the height of the anchor is reduced by folding the hinged blade portions in the direction of the plane when the anchor is stored on its side.

3. A folding plough anchor comprising a pair of blades extending on either side of a plane, said blades coming together in a ridge in said plane and sloping away from each other in the form of a double-bladed ploughshare, each of said blades comprising two blade portions with adja-

cent edges extending generally parallel to said plane when the anchor is unfolded for use, hinge means connecting said blade portions for relative swinging movement, and a brace secured between the respective outer hinged portions of the blades and detachable from at least one of said parts, whereby the height of the anchor is reduced by detaching at least one end of the brace and folding the blades while the anchor is stored on its side.

4. A folding plough anchor comprising a pair of blades extending on either side of a plane, said blades coming together in a ridge in said plane and sloping away from each other in the form of a double-bladed ploughshare, each of said blades comprising a fixed portion rigidly connected to the fixed portion of the other blade and an outer hinged portion forming an extension of the fixed portion when the anchor is unfolded, 15 a detachable brace connected between the hinged blade portions for holding them in extended position, and hinge means connected between the two portions of each blade with the hinge axis spaced from the blade toward said plane and extending 20 generally parallel to said plane, whereby the height of the anchor is reduced by detaching at least one end of the brace and folding the hinged blade portions in the direction of the plane when the anchor is stored on its side.

5. A folding plough anchor comprising a pair of blades extending on either side of a plane, said blades coming together in a ridge in said plane and sloping away from each other in the form of a double-bladed ploughshare, each of said blades 25 being in two parts, hinge means connected between said parts of each blade with the hinge axis offset from the junction of said parts, and a member extending from one of said parts of each blade across one end of the hinge gap to the other part of the blade while the anchor is folded, thereby minimizing the risk of ropes fouling in the open hinge gaps while the blades are folded.

6. A folding plough anchor comprising a pair 45 of blades extending on either side of a plane, said blades coming together in a ridge in said plane and sloping away from each other in the form of a double-bladed ploughshare, each of said blades comprising a fixed portion rigidly connected to the fixed portion of the other blade and an outer hinged portion forming an extension of the fixed portion when the anchor is unfolded, hinge means connected between the two portions of each blade with the hinge axis spaced from the blade toward said plane and extending generally parallel to said plane, and a member extending from the hinged portion of each blade toward and against part of the fixed portion of the same blade while the blade is folded, whereby the blades are foldable to reduce the height of the anchor while it is stored on its side and the members across the hinge gaps minimize the risk of ropes from fouling in the hinge gaps of the folded blades.

Certificate of Correction

Patent No. 2,507,563

May 16, 1950

WILLIAM SCOTT FARREN

It is hereby certified that error appears in the above numbered patent requiring correction as follows:

In the heading to the drawing, line 3, for the filing date "April 13, 1947" read *August 13, 1947*;

and that the said Letters Patent should be read as corrected above, so that the same may conform to the record of the case in the Patent Office.

Signed and sealed this 26th day of December, A. D. 1950.

[SEAL]

THOMAS F. MURPHY,
Assistant Commissioner of Patents.
